LIQUID MOVING APPARATUS

Nikolaus Laing, Stuttgart, Germany

Application December 1, 1955, Serial No. 550,444

Claims priority, application Germany September 13, 1950

6 Claims. (Cl. 103—53)

The present invention relates to pumps.

This application is a continuation-in-part of copending application Serial No. 245,690 filed November 24, 1952, now abandoned and the copending application Serial No. 410,887, filed February 17, 1954, now abandoned, which is a continuation of the aforementioned abandoned application.

Certain known pumps, such as piston displacement pumps, for example, are capable of very efficiently pumping liquids where very high pressures are required. Other types of pumps such as motor driven pumps are capable of very efficiently pumping a high volume of liquid at relatively low pressure. However, neither of these pumps is capable of efficiently pumping relatively small volumes of liquid at relatively low pressures. Although certain motor driven pumps have been provided for this purpose, these conventional pumps have the disadvantage of requiring a very special seal to seal the connection between the drive shaft and the motor from the liquid which is pumped. Where these motors are very small so much friction is lost in the seal itself that the pump operates at a very low efficiency. Furthermore it is very difficult to provide with pumps of this latter type a sealing material which is capable of being used with all types of liquids, so that these pumps work best only with certain liquids and do not have a flexibility which would be desired.

One of the objects of the present invention is to overcome the above drawbacks by providing a pump which is capable of efficiently displacing a relatively small volume of liquid at a relatively low pressure.

Another object of the present invention is to provide a pump which is capable of being used with many different liquids because the pump is not provided with any seal which will be attacked by some liquids and not others.

A further object of the present invention is to provide a pump which has a casing a part of which can be removed in such a way that the pump may serve the additional purpose of simply mixing a fluid or performing a similar function rather than pumping.

An additional object of the present invention is to provide a pump which is capable of moving a liquid displacing means simply in response to excitation from an alternating source of current.

A still further object of the present invention is to provide in a pump of the above type a very efficient liquid displacing means which is of an exceedingly simple construction.

Also, the objects of the present invention include the provision of a pump structure capable of accomplishing all of the above objects and at the same time being composed of simple and ruggedly constructed elements which are very reliable in operation and which may be very easily assembled and disassembled.

With the above objects in view the present invention mainly consists of a pump which includes an elongated tube means having an inlet end and an outlet end and

2

having a chamber communicating with the outlet end thereof. An oscillating means is carried by the tube means adjacent the outlet end thereof and defines part of the chamber of the tube means. A shaft is fixed to the oscillating means to be reciprocated along its axis thereby and extends from the oscillating means along the interior of the tube means to a point adjacent the inlet end of the tube means. A liquid displacing means is fixed to the shaft in the interior of the tube means adjacent its inlet to reciprocate with the shaft in order to displace liquid along the interior of the tube means from its inlet to its outlet.

The novel features which are considered as characteristic for the invention are set forth in particular in the appended claims. The invention itself, however, both as to its construction and its method of operation, together with additional objects and advantages thereof, will be best understood from the following description of specific embodiments when read in connection with the accompanying drawings, in which:

Fig. 1 is an elevational partly sectional and partly diagrammatic view of a pump constructed according to the present invention;

Fig. 2 is a partly sectional elevational view of another embodiment of a pump according to the present invention;

Fig. 3 is a sectional elevational fragmentary view showing the structure of the pump adjacent its inlet end and showing the structure of a displacing means which

30 displaces liquid in the pump; and

Fig. 4 is a sectional view taken along lines IV—IV of Fig. 3 in the direction of the arrows.

Referring now to the drawings, it will be seen that the pump structure illustrated therein is portable and is 35 adapted to be inserted through the opening of a container into the interior of the latter for pumping a liquid from the interior of such container. As is apparent from Fig. 1, the pump illustrated in this figure has a handle at its top end, this handle accommodating an electrical lead which may be connected to any suitable source of 40 alternating current. Also this handle is provided with a manually operable switch for turning the pump on and off. The handle of the pump is carried by a tube means for conducting liquid along the interior of this 45 tube means. This tube means includes a portion 1 in the form of a chamber located beneath the handle and communicating with an outlet 10 of the tube means. Any suitable hose or pipe may be connected to the outlet 10 for directing liquid away from the pump. The chamber

50 1 has removably connected thereto an elongated tube 3 of the tube means, the bottom end of this tube 3 being open and being provided with cutouts 9, so that the bottom end portion of the tube 3 serves as the inlet for the tube means 10, 1, 3. The elongated tube 3 of this tube

55 means is threaded to the chamber 1 through the medium of an annular internally threaded ring 4 having at its bottom end an inwardly extending flange which overlaps an outwardly extending flange carried by the tube 3. This flange of the tube 3 rests against the bottom end face of the chamber 1 and the threaded ring 4 is 60 threaded to the chamber 1 in the manner indicated in Fig. 1 for fixing the tube 3 to the chamber 1.

The tube means carries at the chamber 1 an electrical 65 oscillating means which is excited by the alternating source of current. This electrical oscillating means includes a winding 20 which is located about a core 19 in which an upper end portion of a shaft 6 is slidable. The core 19 is fixed to a bottom annular stop 23 which forms part of the above described solenoid structure. An armature 2 is adapted to be oscillated when the solenoid is 70 excited by alternating current, and this armature 2 thus is fixed to the shaft 6 in the manner indicated in Fig. 1.

A spring 21 is coiled about the armature 2, bears against the flange thereof, and bears against the stop 23; so as to urge the armature 2 and the shaft 6 therewith in a downward direction, as viewed in Fig. 1. When the solenoid is periodically excited the armature 2 moves upwardly, and when the excitation of the solenoid is zero the spring 21 urges the armature and the shaft 6 therewith downwardly, as viewed in Fig. 1, so that in this way the shaft 6 is operatively connected to the oscillating means to be reciprocated by the oscillating means along the axis of the shaft 6.

The above described oscillating means is located in a housing which is located in and defines part of the chamber 8 formed by the portion 1 of the tube means. The housing has a bottom wall formed with an opening through which the shaft 6 slidably extends, and a seal in the form of a bellows 7 is fixed at one end to the housing of the oscillating means and at its opposite end to the shaft 6 so that in this way the interior of the oscillating means which is operatively connected to the shaft 6 is sealed off from the liquid which moves along the interior of the tube means. It will be noted that the shaft 6 does not frictionally rub against the seal, as is the case where a pump shaft is driven by a motor, so that with the structure of the invention there is no friction loss to reduce the efficiency of the pump.

Adjacent the inlet end of the tube 3, the shaft 6 carries a liquid displacing means 5 which reciprocates with the shaft 6 and is located in the interior of the tube means in order to displace liquid along the interior of the tube means from its inlet to its outlet. The construction of the liquid displacing means 5 will be described below in detail with respect to Fig. 3.

Furthermore, a valve 4 is fixed in the interior of the tube 3 below the liquid displacing means 5 between the latter and the inlet of the tube means. The details of the valve 4 also will be described below in connection with Fig. 3. This valve 4 has a central hub portion provided with an elongated bore into which the lower free end of the shaft 6 slidably extends so that in this way the shaft 6 is guided for reciprocating movement along its axis.

When the bottom end portion of the structure of Fig. 1 is set into a body of liquid and the oscillating means is connected to a source of alternating current to be excited thereby, the reciprocating liquid displacing means 5 will pump the liquid along the interior of the tube means 10, 1, 3 from its inlet end to its outlet end. It should be further noted that if the ring 4 is unthreaded from the chamber 1, the tube 3 may be removed and in this event only the liquid displacing means 5 can be located in a body of liquid so that the shaft 6 may then be reciprocated to oscillate the liquid displacing means 5 which under these circumstances will simply act in order to agitate a liquid for any desired purpose.

According to the embodiment of the invention which is shown in Fig. 2, the oscillating means indicated with the numeral 2 is provided with a cylindrical portion 13 having annular grooves formed in its outer surface. This cylindrical portion 13 is in the nature of a piston having a fairly tight sliding fit in the chamber portion of the tube means shown in Fig. 2. This chamber portion communicates with the outlet 10 in the same manner as the structure of Fig. 1, and the elongated tubular portion of the tube means which leads to the chamber which communicates with outlet 10 is of the same construction as the tube 3 of Fig. 1 except that it is rigidly connected to the remainder of the tube means. Thus, with the embodiment of Fig. 2 although the elongated portion of the tube means through which the shaft extends cannot be removed, the entire tube means can be removed by being slipped off from the cylindrical portion 13 of the housing of the oscillating means 2 so that in this way the structure of Fig. 2 also may be used for liquid agitating purposes as well as for pumping purposes.

A further feature shown in the embodiment of Fig. 2 is that no valve corresponding to the valve 4 of Fig. 1 is provided with the embodiment of Fig. 2. Instead only a liquid displacing means 15 which may be identical with the liquid displacing means 5 is connected to the shaft 6 for reciprocation therewith. This liquid displacing means 15 is in itself capable of displacing the liquid upwardly along the tube because the liquid is not free to fall down by the liquid displacing means 15 as easily as it is moved upwardly by this liquid displacing means, as will be evident from the description of Fig. 3 below. With the embodiment of Fig. 2 the bottom end portion of the shaft which carries the liquid displacing means is guided in a bore of the hub of a centering means 14 which is simply in the form of an annular ring fixed to the interior of the tube and having a plurality of radially extending fins extending inwardly from this annular ring and fixed to the hub formed with the bore which guides the shaft 6. The radially extending fins of the centering means 14 are spaced from each other and do not materially obstruct the flow of liquid along the interior of the tube means.

As is shown in Fig. 3, the liquid displacing means 15, 16 which is identical with the liquid displacing means 5 of Fig. 1 or 15 of Fig. 2, is in the form of a pair of annular channels of substantially parabolic cross section having their interiors directed toward the outlet of the tube means. These annular channels which constitute the liquid displacing means gradually reduce in cross section as they approach the inlet and gradually increase in cross section as they approach the outlet, so that when the liquid displacing means is displaced downwardly toward the inlet it presents very little resistance to the liquid, while when the displacing means is displaced upwardly toward the outlet it will provide a great resistance to the movement of the liquid and will in fact lift the liquid toward the outlet. Thus, as the liquid displacing means is reciprocated back and forth it will displace the liquid toward the outlet of tube means. As is apparent from Fig. 3 the particular liquid displacing means disclosed therein includes two annular channels one of which is located within the other, and these annular channels each have an outer edge portion which extends upwardly beyond its inner edge portion. A sleeve is fixed to a shaft portion which is in turn fixed to the elongated shaft 6 which is hollow in the example shown in Fig. 3, and this sleeve has fixed thereto a plurality of fins 16 which extend radially outward from the axis of the shaft, as is evident from Fig. 3. Thus, these fins are fixed to the shaft 6 for reciprocation therewith. The outer edges of the annular channels which form the liquid displacing means extend into cutouts of the fins 16 and are rigidly fixed to the latter as by being welded thereto, so that in this way the fins 16 and the annular channels are fixed to each other and to the shaft 6 for reciprocation therewith.

As is apparent from Figs. 3 and 4, the valve 4 of Fig. 1 is constituted by a plurality of radially extending rigid members 18 which are fixed at their inner end to a hub formed with a bore in which the bottom end portion 60 of the shaft 6 is freely slidable. The outer ends of these rigid members 18 are fixed to an annular ring which is in turn fixed to the interior of the tube 3 in the manner indicated in Fig. 3, just above the inlet of the tube. The elongated rigid members 18 fixedly carry a pair of annular channels 17 which are identical with the annular channels of a displacing means. Thus, while these annular channels 17 remain stationary they nevertheless act as a valve in that they render it easy for the liquid to flow upwardly by the channels 17 but at the same time 70 prevent liquid from easily flowing downwardly past the channels 17, so that in this way the channels 17 act in the nature of a non-return valve. However, as is apparent from the embodiment of Fig. 2, the structure of the invention may operate without this valve structure. Thus, it is apparent from the above description that

the pump structure of the invention is composed of relatively simple rugged elements which are capable of very efficiently pumping relatively small amounts of liquid at relatively low pressure. The material of the bellows 17 may resist attack of all sorts of liquids and since it is not subject to frictional rubbing it will have a life far greater than a conventional sealing gland through which a shaft rotatably passes. Furthermore it is apparent that the above described structure can be used simply for liquid agitation purposes, if desired, and in order to accomplish this result it is only necessary to remove the outer casing of the pump which guides the liquid, this removal being accomplished in a very simple manner. With the structure of Fig. 2, the portion 13 of the housing 2 of the oscillating means has a sufficient friction fit with the tube means to carry the latter, although, if desired screws may pass through the wall of the tube means into one of the annular grooves shown in the cylindrical portion 13 in Fig. 2 in order to guarantee the connection between the tube means and the oscillating means. With this latter arrangement it is only necessary to turn such a screw outwardly in order to release the connection between the oscillating means and the tube means. Furthermore, it will be noted that the above described structure is capable of using the alternating current of the power supplied by a public utility in order to excite the pump.

It will be understood that each of the elements described above, or two or more together, may also find a useful application in other types of pumps differing from the types described above.

While the invention has been illustrated and described as embodied in pumps capable of pumping as well as agitating a liquid, it is not intended to be limited to the details shown, since various modifications and structural changes may be made without departing in any way from the spirit of the present invention.

Without further analysis, the foregoing will so fully reveal the gist of the present invention that others can by applying current knowledge readily adapt it for various applications without omitting features that, from the standpoint of prior art, fairly constitute essential characteristics of the generic or specific aspects of this invention and, therefore, such adaptations should and are intended to be comprehended within the meaning and range of equivalence of the following claims.

What is claimed as new and desired to be secured by Letters Patent is:

1. A pump comprising, in combination, elongated tube means having an inlet end and being provided with a chamber distant from said inlet end, said tube means having an outlet communicating with said chamber so that when liquid flows along the interior of said tube means from said inlet to said outlet thereof the liquid flows through said chamber; oscillating means carried by said tube means and including a housing having a high thermal conductivity and defining part of said chamber; a shaft fixed to said oscillating means to be reciprocated along its axis thereby and extending from said oscillating means along the interior of said tube means to a point adjacent said inlet end of said tube means; sealing means connected to said housing and said shaft for preventing entrance of liquid into said housing; liquid displacing means carried by said shaft adjacent said inlet end of said tube means in the interior of and for movement relative to the latter for displacing liquid toward said chamber when said shaft is reciprocated by said oscillating means; and means removably connecting a portion of said tube means in which said liquid displacing means is located from the remainder of said tube means so that when said portion

of said tube means is removed from the remainder of said tube means, said liquid displacing means may be used to agitate a liquid.

2. A pump as defined in claim 1 wherein said liquid displacing means being composed of elements which gradually reduce in cross-section as they approach said inlet and which gradually increase in cross-section as they approach said outlet, so that when the liquid displacing means is reciprocated in said tube means toward said inlet thereof said liquid displacing means will provide substantially less resistance to the movement of the liquid in said tube means than when said liquid displacing means is displaced toward said outlet end of said tube means.

3. A pump as recited in claim 2 and wherein said liquid displacing means includes at least one annular member through which the axis of said shaft passes, said annular member having a substantially parabolic cross section and having an end portion adjacent said inlet which is of a smaller width than the opposite end portion thereof.

4. A pump as recited in claim 2 and wherein said liquid displacing means is in the form of an annular channel whose interior is directed towards said outlet end of said tube means, said channel having a substantially parabolic cross section and being located about the axis of said shaft.

5. A pump as recited in claim 2 and wherein said liquid displacing means includes a plurality of fins fixed to and extending radially from said shaft; and at least one annular channel of substantially parabolic cross section located about said shaft and having its interior directed toward said outlet of said tube means, said channel having one edge portion which extends beyond the other edge portion thereof and which is fixed to said fin.

6. A pump comprising, in combination, oscillating means including a housing of high thermal conductivity and having an outer cylindrical surface portion; elongated tube means having a cylindrical portion in which said housing is received with a close fit so that said housing forms with a portion of said tube means a chamber defined in part by said housing, said tube means having an outlet communicating with said chamber and an elongated portion also communicating with said chamber and terminating at an end distant from said chamber with an inlet into said tube means; a shaft fixed to said oscillating means to be reciprocated along its axis thereby and extending from said oscillating means through said chamber and along the interior of said tube means towards an inlet thereof; sealing means connected to said housing and said shaft for preventing entrance of liquid into said housing; and liquid displacing means carried by said shaft adjacent said inlet of said tube means in the interior of the latter so that when said shaft is reciprocated along its axis said liquid displacing means will displace liquid along the interior of said tube means towards said outlet thereof, said housing with said oscillating means being easily removable from said cylindrical portion of said elongated tube means so that said liquid displacing means may be used to agitate a liquid when said housing is removed from said tube means.
